US00D992404S

(12) **United States Design Patent** (10) **Patent No.:** **US D992,404 S**
(45) **Date of Patent:** **** Jul. 18, 2023**

(54) **ANCHOR DEVICE**

(71) Applicant: **GRIPPLE LIMITED**, Sheffield (GB)

(72) Inventor: **Samuel White**, Sheffield (GB)

(73) Assignee: **GRIPPLE LIMITED**

(**) Term: **15 Years**

(21) Appl. No.: **29/803,806**

(22) Filed: **Aug. 16, 2021**

(51) LOC (14) Cl. **08-08**

(52) U.S. Cl.

USPC **D8/382**

(58) **Field of Classification Search**

USPC D8/349, 354, 373, 380, 382, 383;
D25/199

CPC E04B 2001/1996; E04B 1/4121; E04B

(57) **CLAIM**

The ornamental design for an anchor device, as shown and described.

DESCRIPTION

FIG. 1 is a back view of the anchor device;

FIG. 2 is a bottom view thereof;

FIG. 3 is a front view thereof;

FIG. 4 is a left side view thereof;

FIG. 5 is a perspective view thereof;

FIG. 6 is a right side view thereof; and,

FIG. 7 is a top view thereof.

The broken lines in the drawings illustrate portions of the anchor device and form no part of the claimed design.

1 Claim, 4 Drawing Sheets
